US0D1026010S

(12) **United States Design Patent** (10) Patent No.: **US D1,026,010 S**
(45) Date of Patent: ** May 7, 2024

(54) **ENERGY MODULE WITH ALERT SCREEN WITH GRAPHICAL USER INTERFACE**

(71) Applicant: **Cilag GmbH International**, Zug (CH)

(72) Inventors: **Brendan J. Oberkircher**, Cincinnati, OH (US); **Cory G. Kimball**, Hamilton, OH (US); **Matthew C. Miller**, Cincinnati, OH (US); **Jacob S. Childs**, Huntington Beach, CA (US); **Leonardo N. Rossoni**, Rahway, NJ (US)

(73) Assignee: **Cilag GmbH International**, Zug (CH)

(**) Term: **15 Years**

(21) Appl. No.: **29/816,425**

(22) Filed: **Nov. 22, 2021**

Related U.S. Application Data

(63) Continuation of application No. 29/704,617, filed on Sep. 5, 2019, now Pat. No. Des. 939,545.

(51) **LOC (14) Cl. 13-03**

(52) **U.S. Cl.**

USPC **D13/162; D14/486**

CLAIM

The ornamental design for an energy module with alert screen with graphical user interface, as shown and described.

DESCRIPTION

FIG. 1 is a front view of an energy module and display screen; and,

FIG. 2 is a perspective view of the energy module and display screen of FIG. 1.

In the figures, the broken lines illustrate environment and form no part of the claimed design.

1 Claim, 2 Drawing Sheets
